CARBON PAPER INSERTING MACHINE

William B. Austin, Ridgewood, N.J. (Recording & Statistical Corporation, 100 Ave. of the Americas, New York 13, N.Y.)

Filed Mar. 21, 1955, Ser. No. 495,571

17 Claims. (Cl. 270—58)

This invention relates to carbon paper inserting machines for inserting sheets of carbon paper between the sheets of paper of a stock, of a group, or of a case.

An object of the invention is the provision of means for stacking sheets of paper and the provision of other means for interspersing a sheet of carbon paper or the like between each two adjacent sheets.

A further object of the invention is the provision, in a paper handling machine, of suction cup means to jointly handle a sheet of carbon paper and a sheet of paper, thicker than carbon paper by means of twin suction cups, one of which handles the sheet of paper only, and the other of which handles a sheet of carbon paper "backed up" or reinforced by a sheet of paper, or by the same sheet handled by said first suction cup.

Yet another object of the invention is the provision of means to rotatably support a roll of carbon paper, means to feed carbon paper from said roll, settable means to gauge the length of carbon paper taken from said roll, means to cut off a gauged length of carbon paper from said roll, and means to deliver the cut off length to a point spaced apart from said means to cut off.

Other objects and advantages of the invention will be apparent to those skilled in the art upon a study of this specification and the accompanying drawings.

Referring to the drawings which are given to illustrate the invention and the method of practising it.

Figure 1 is an elevational view taken along the line 1—1 of Figure 2 and showing the relation between the carbon paper handling, cutting off and delivery means, and the stacking mechanism;

Figure 2 is an elevational view taken along the line 2—2 of Figure 1, the carbon paper chute having been omitted for the sake of clarity;

Figure 3 is a view taken along the line 3—3 of Figure 2, the top being on the left;

Figure 4 is an elevational view taken along the line 4—4 of Figure 3 and showing my novel means of driving the carbon paper mechanism from the stacking mechanism below;

Figure 5 is a view taken along the line 5—5 of Figure 3;

Figure 6 is an enlarged fragmentary view of the twin suction cups, showing how one of them engages the paper and how the other engages the carbon paper backed up and reinforced by the paper;

Figure 7 is a fragmentary view showing the method of clamping the main frame and the sub-frame in any adjusted relation;

Figure 8 is a plan view as seen along the line 8—8 of Figure 4;

Figure 9 is an enlarged detailed view of the clutch element as seen along the line 9—9 of Figure 8;

Figure 10 is an enlarged fragmental side elevational view with parts in section of a block 228 and associated parts;

2

Figure 11 is a detailed elevational view taken along the line 11—11 of Figure 10;

Figure 12 is a circuit diagram showing the knife actuating solenoid circuit.

5 Figure 13 is a diagrammatic representation of mechanism for swinging the oscillating arms of the sheet feeding mechanism;

10 Figure 14 is a diagrammatic representation of mechanism for oscillating a shaft carried by the oscillating arms and in turn carrying twin suction cups; and

15 Figure 15 is a diagrammatic representation of driving and air control means.

Referring first to the upper portions of Figures 1, 2, and 4, my machine for handling rolls of carbon paper will first be described.

A frame comprised of a main end plate 10, and a second main end plate 11 held in spaced parallel relation therewith by means of spacer or distance rods 12, 13, and 14 forms a support for the carbon paper mechanism.

20 The end plate 10 has an extension 15 formed integral therewith and it has a vertical slot 16 formed therein with a semi-circular bottom 17, and it accommodates one end of a shaft 19, which supports a roll 9 of carbon paper.

25 The end plate 11 has an extension 20 formed integral therewith, and this extension has a vertical slot (not shown) identical with the slot 16 with its semi-circular bottom to accommodate the other end of the shaft 19 supporting the roll of carbon paper. The shaft 19, Figure 1 has a drum 21 secured thereon to serve as a brake drum for preventing the carbon paper from "over running."

30 Pivotedly mounted on the plate 10 by virtue of being journaled on a stub shaft 22, is a lever 23. Pivotedly connected to the upper end of the lever 23 by means of a clevis pin 24, extending through aligned holes in a bifurcated boss 26, is a braking sector 25, which has a frictional lining 27 in cooperative relation with the drum. A stud 28, carried on the extension has one end of a spring 29 secured thereto, and the other end of said spring is secured to a stud 30 carried by the lever 23, so that the lever 23 is urged in a clockwise direction about the stub shaft 22 by the spring 29.

35 The lower end 31 of the lever 23 is bifurcated and carries a stud 32 upon which a roller 33 is journaled. Fixedly mounted on the end plates 10 and 11 is a shaft 34, upon which a roller 35 is journaled.

Adjustable sub-frame

40 Within the fixed frame described above is adjustably carried a sub-frame comprising an end plate 36 and a similar end plate 38. The end plate 36 is in contact with the main end plate 10, and likewise the end plate 38 is in contact with the main end plate 11.

45 Formed in the array of main and sub-frame end plates are aligned holes to accommodate a main shaft 37, see Figure 3 also. The holes in the main plates 10 and 11 carry suitable bearings 41 and 42 respectively. Secured on the end plate 36 by means of cap screws 43 is a sector plate 44 which is arcuately notched to provide a depending portion 45 overhanging the main end plate 10, as shown in Figure 7.

50 Secured on the end plate 38 by means of cap screws 39 is a sector plate 40 having a depending portion 46 overhanging the main end plate 11 in the same manner as the depending portion 45 does the main end plate 11.

55 Carried on the shaft 37 as best seen in Figure 3 is a feed disc assembly 48, having a hub 47 embracing said shaft. Mounted on the end plate 36 is an index plate 50 which is arcuate in form. The index plate 50 is mounted on studs or the like 49 by means of screws 49a. Also carried on the shaft 37 adjacent to the feed disc

assembly 48 and cooperating therewith is a crank member 52 which may be secured on the shaft 37 by means of a cap screw 51 passing through a split boss thereon.

Cooperating with the index plate 50 is a settable indexing arm 53 which has a pointer 54, and a clamping bolt 55 which extends through an arcuate slot 56 formed in the index plate 50. The index plate may carry graduations (not shown) which may be traversed by the pointer 54 when it is desired to set the device to cut carbon sheets a wanted length.

The indexing arm 53 has a tripping element 57 formed integral therewith and its function will presently be described.

For drawing the carbon paper strip 125 from the roll 9, I provide a pair of cooperating rollers 58 and 60 which frictionally engage the carbon paper strip or web 125. The axes of rollers 58 and 60 lie on a plane at least approaching the horizontal and they are geared together by a gear 59 on the roller 58 meshing with a gear 61 on the roller 60.

The roller 58 has a shaft 62 which is supported by aligned bearings in the main end plates 10 and 11. This roller has spaced apart heads 64 and 65 on the shaft 62, and between these heads the roller is in the form of a firm tube of neoprene, rubber or the like. Secured on the shaft 62 are also secured twin spools or rings, and adjacent thereto are twin ratchet wheels 68 and 69. A pawl 70 engages the ratchet wheel 68.

The roller 60 has a shaft 71 which is supported by aligned bearings in the main end plates 10 and 11. These bearings are in spring loaded brackets which perform certain functions. Referring to Figure 4, a bearing bracket 76 has a bearing hole 75 therein formed preferably at a mid-point therein, and a second bearing hole near one end thereof. The shaft 71 of the roller 60 is journaled in the hole 75. A shouldered screw 77 is journaled in the second bearing hole and is screwed into the frame member 38. A spring post 78 on the bracket has one end of a spring 89 connected thereto, and the other end of the spring is connected to a spring post on the frame member 38.

A second bearing bracket 83 has a bearing hole 81 therein into which the shaft 71 is journaled. (This is the other end of the shaft 71 supporting the roller 60). This bracket also has a second bearing hole in which a shouldered screw 82 is journaled. This screw is threaded into a tapped hole in the frame member 36. A spring post 84 is carried by said bracket, and one end of a spring 86 is connected to it. The other end of the spring 86 is connected to a spring post 85. The combined urges of the springs 89 and 86 maintain the rollers in frictional engagement with the web of carbon paper 125 between them and also maintains the gears 59 and 61 on the rollers 58 and 60 respectively in mesh with one another and thereby prevents them from slipping. The carbon paper 125 after passing between the rollers 58 and 60, passes through longitudinal slot 37 formed in a movable knife member 88, and thence it passes into a telescoped carbon paper guide array 134, which will presently be described.

Cooperating with the knife member 88 is a stationary knife member 89, which may be provided with an angle iron brace member 90 to prevent it from flexing. The stationary knife member 89 is secured into the frame 36, 38 in any suitable manner, for example, by means of screws 91 tapped into the end plates 36 and 38.

A shaft 92 is journaled in suitable bearings such as the bearing 93 carried by the plate 38. Secured on the shaft 92 is a curved supporting bar 94 which is adjacent to a solenoid 95, to be presently described; and a second curved supporting bar 96 is also secured on the shaft 92 in spaced apart relation to the curved bar 94. The movable knife 88 is supported by said curved supports in the following manner. A plate member 98 has a tongue portion 99 which extends into a slot 100 formed in the

curved support 94, as may be best seen in Figure 3, and is secured therein by means of a pin 101, passing through aligned holes formed in the support 94 and in the tongue portion 99. The curved support 96 has a slot 102 formed therein, and forming a working fit in said slot is a tongue portion 104 carried by a plate member 103. The tongue portion 104 is secured in the slot 102 by means of a pin 105, passing through aligned holes in the end of the curved support and a hole formed in said tongue, is a pin 105. The plates 98 and 103 are secured to the knife member 88 in spaced apart relation by means of screws 106.

The solenoid 95 comprises a frame 107 carrying a solenoid winding 108, a base 118 has an angle portion 116 which is secured to the end plate 36 by means of screws. A plunger 109 is reciprocally carried in a passage formed within said winding, and is joined to a connecting link 110 by a pin 119 (Figure 5), and the link and the plunger are normally urged to the left by means of a spring 111 which has one end connected to the pin 113 and the other end connected to the body through a pin or post 112, so that as the solenoid is energized (in a manner to be presently described) the plunger is urged to the right as viewed in Figure 5.

Fixed on the shaft 92 is a lever 115 which has its outer extremity 121 set into a passage 120, extending through the link member 110, and is pivotally secured therein by means of a clevis pin 114 extending through aligned holes in member 110 and the portion 121 of the lever 115 so that the movement of the solenoid plunger 109 to the right as described above into the solenoid winding causing the shaft 92 to move through an arc in a clockwise direction (as viewed in Figure 5). This movement is imparted to the blade 88 through the curved supports 94 and 96, and causes the blade 88 to move downwardly as seen in Figure 5, in cooperation with the stationary blade 89, thereby cutting off a predetermined length of carbon paper 125a from the carbon paper web 125.

A post 122 on the frame carries an adjustment screw 123 with a locknut thereon for locking the screw in any adjusted setting, for example the screw as shown in Figure 5 is set to adjust the stoppage of the solenoid plunger to a most efficient normal position, through the lever 115.

The curved support 94 has hingedly connected thereto a screw 126 by a pivot pin 128. This screw passes through a hole in the movable knife 88 (see Figure 1) and a spring on the screw bears against the knife 88 and maintains it in contact with the stationary blade 89, and the tension of the spring may be adjusted by means of a nut 127.

The curved support 96 has hingedly connected thereto by means of a pivot pin 129, a screw 130 which carries a spring 131 in contact with the knife 88 and retained on the screw by an adjustment nut 132. The spring urges the knife 88 into cooperative engagement with the knife 89, and the tension of this spring is also regulated by the adjustment nut 132, Figure 4.

The telescoped carbon paper guide array, referred to above, may be best seen in Figures 1, 3 and 4 and is generally designated by the numeral 134, and is comprised of one inner telescoped member 135 and an outer and lower member 133. The member 135 has ears 136 on each end thereof, through which screws 137 pass to threadedly engage the end plates 36 and 38 respectively.

The member 133 has ears 138 on each end thereof through which screws 139 pass to threadedly engage threaded holes in the end plates 10 and 11. By this arrangement the chute 133 is continuous for all adjustments of the sub-frame 36, 38 relative to and within the main frame 10, 11.

A boss 152 has a spring tightening stud 153 which cooperates with an internal hub (not shown) and carries a spring drum 155 having a spring therein which in any well known manner may be given any desired tension

and locked by means of a nut 156 to retain the same. The drum 155 is flanged to carry a suitable flat belt 157 which spans the drum 155 and the spool 150 with several convolutions to effect a desired follow up of the roller 58 under certain conditions.

A belt encircles the feed disc 48, and also has several convolutions about the spool 151, so that, due to the fact that the spool 150 and the spool 151 are fixed together, the tension of the spring drum 155 is imparted to both the feed disc 48 and to the roller 58.

A boss 159 has a spring tightening stud 160 which cooperates with an internal hub (not shown) and carries a spring drum 161 which may be set for a desired tension and locked in such setting by a nut 162. The drum 161 is grooved to carry several convolutions of a belt 163 thereabout.

A double grooved pulley 164 has a hub 165 which fits on the shaft 37, and one grooved portion 166 has the belt 163 secured thereto.

The other grooved portion 167 has a belt 168 making several convolutions about it above a point of securement and the other end of this belt has a loop 169 formed therein. The belt 168 passes diagonally down from the pulley 164, passes around an idler roller 171 on the main frame plate 11, which is journaled on a stud 72. The loop 169 embraces a shaft 170 to be presently described.

The pulley 164 has a pin 171 thereon which extends parallel to the shaft 37. A clutch element has a hub 172 and a flange 173 formed integral therewith. This element is fixed on the shaft 37, while the pulley 164 is free on the shaft, and the pin 171 clears the flange 173. A pawl member 174 (Figure 9) is pivotally carried on the flange 173 by means of a shouldered screw 175 and it is urged outwardly (in a counter-clockwise direction) by a spring 177 against a stop pin 178 (Figure 9). The pawl 174 has a tail carrying a hole 270 adjacent to the shaft 37. One end of the spring 177 connects to the hole 270, and the other end engages a post 271 on the flange 173. The engaging end 176 of the pawl member cooperates with the pin 171 when the pulley 164 is rotated counter-clockwise (as viewed in Figure 4) due to the pull on the belt 168 as the shaft 170 is moved from the solid position to the dotted position shown in Figure 4. Now when the movement of the shaft 170 is from the dotted position, back to the solid position, the urge of the spring drum (which had been increased by the first movement just described) causes the belt 168 to be pulled back and kept taut. Thus the pull of the belt 168, as above described, is the only power I supply to the carbon paper measuring and cutting device, with the exception of the power delivered to the solenoid 108.

The above described mechanism can be set to deliver sheets of carbon paper cyclicly, and it may be used in combination with a collator in a manner to intersperse the carbon sheets between the sheets being collated.

An example of a collator and sheet stacker to cooperate with my carbon paper mechanism is described in Patent Number 2,639,917 which issued to Keith S. Macey on May 26, 1953.

The frame of the collating portion of the machine embodies a base (not shown) and end walls 181, and preferably has one or more intermediate walls parallel to end walls 181, but these are not shown in the drawing. All of the walls are joined by longitudinal members which may include a pair of braces (not shown) near the bottom of the machine and solid bars 183 and 184 and a tubular bar 185.

Shafts 186 and 187 extend the full length of the machine, having bearings in the end walls 181 and preferably also in the intermediate walls. The shaft 186 rotates continuously, making one revolution for each machine cycle. In every cycle a sheet is fed from the top of each pile of sheets onto a tray 188 which runs lengthwise through the machine. This tray has a longitudinal slot 189 through which a series of pins 190 extend. These

pins which are spaced apart the same distance as the hoppers are mounted on an endless conveyor chain 191 which operates intermittently. It is advanced after each feeding operation a distance equal to the distance between one of said pins and the next succeeding one, whereby the sheets from the various hoppers are collected in stacks and delivered at the end of the upper run of chain travel. The sheets are fed by means of suction cups which will be presently described and one of the cups 10 engages one of the sheets and the other cup engages a carbon sheet after it has passed down the chute 134 to the stack of sheets and just as it is being cut off from the web, so that the carbon is under control at all times.

As explained above the picking up, by means of a suction cup, of the carbon sheet backed up by the heavier sheet prevents the suction or vacuum from doing any damage to the carbon sheet, as would be the case if the carbon sheet were handled without the reinforcing effect of the heavier sheet.

An electric motor (not shown) drives a speed reducer, (also not shown) and the speed reducer via a belt 191 drives a shaft 193 and a second shaft 194. A shaft 193 and a second shaft which carries a sprocket (not shown) is spanned by a drive chain 195 and this 25 chain in turn drives a sprocket 192. Between the sprocket 192 and the sprocket 191 is a one revolution clutch which is automatically actuated once during each machine cycle for advancing the chain a distance equal to the distance between successive pins 190. The shaft 30 186 is driven from the shaft 193 on a one to one ratio by means of the belt 269.

A plurality of upwardly extending arms 198 are generally in the shape of the numeral 7 and are clamped to the oscillating shaft 187, for example, by means of 35 the split boss and the cap screw shown. In the free ends of the arms 198, there is journaled a hollow shaft 170 which extends the length of the machine. This hollow shaft is closed at its ends and is subjected to negative pressure or vacuum by means of a flexible hose 200

40 which communicates with the shaft adjacent to the middle thereof. The other end of the hose 200 is connected with the inlet side of a vacuum pump (shown in Figure 15). The shaft 170 opposite each hopper carries a pair of sucker supporting arms 201 each having twin sucker heads 199, 202 and these sucker heads are connected with the interior of the hollow shaft 170 by flexible conductors 203. In order to permit adjustment of the degrees of suction there is provided opposite each hopper a fitting 204 to which the conductors 203 50 are connected and each fitting carries a needle valve 205.

It is necessary to operate linkages by means of which the shaft 187 is oscillated to move the hollow shaft 170 from the full line position of Figure 4 to the dotted position thereof and back again to its normal position

55 in each machine cycle. During this cycle the hollow shaft 170 is oscillated in the arms 198 to raise and lower the sucker heads at the proper points in the cycle, (one of these points being the position shown in solid lines and the other being the position shown in dotted lines). The 60 mechanism for accomplishing these movements per se forms no part of the present invention but means for effecting such movements are shown in Figures 13, 14 and 15, and will presently be described. The pile elevating mechanism for maintaining the top of the pile at 65 the proper level for cooperation with the sucker heads during the operation of the feeder will now be described.

The hopper for each pile comprises upper and lower side rails 207 and 208 which have holes to receive longitudinal bars 184 and 185 and are clamped to those bars by screws 209 and 210 extending across slots formed in the rails between the ends thereof and the holes for the bars 184 and 185. These side rails 207 and 208 support, by means of suitable fastenings, the upright corners 211 of the hopper which constitute guides for the front and side edges of the pile. At the rear of

the pile the rails 207 support short uprights 212 which are adjustable forwardly and backwardly to a limited extent. In these uprights is mounted a rod 213 which supports a rear guide 214 that may be adjusted to a selected position along the length of the rod.

The tubular member 185 acts as an air blast manifold closed at one end and it has its other end connected by a conductor 215 to the outlet side of an air pump. At a point opposite each hopper a nipple 216 connects the tube 185 with a hose 217 which extends to the lower end of a pipe 218. The pipe 218 is supported in a block 219 which is adjustable along the tubular pipe 185. At its upper end the pipe 218 is provided with a slot 220 through which air is discharged against the sheets at the top of the pile for separating the upper sheets at the top of the pile. A plate 222 is movable up and down between and behind the corner members 211 of the hopper. Upon the plate 222 a sheet 223 of heavy cardboard the same size as the sheets of the pile may be placed. This plate is rigidly carried on the upper end of a rack 224 which is movable up and down in guides 225 and 226 that are carried by a plate 227 which is bolted to one edge of a heavy plate or block 228. These blocks are provided with holes to receive the brace bar 183. Each block is slotted as at 229 and a screw 230 is mounted in the block and threaded at 231 in order to clamp the block firmly upon the brace bar. All of the blocks therefore are carried by the bar or shaft 183 and the pile supporting racks are in turn carried by the individual blocks. The shaft 186 extends through all of the blocks with a supplemental bearing in each block. An eccentric 233 is mounted upon and secured to the shaft 186 adjacent to each block 228, for example by means of a set screw 234. In bracing the eccentric near an extremity thereof is a ring 235 and the eccentric is free to turn within the ring; however in order to hold the two parts against relative movement lengthwise of the shaft 186, a set screw 235 projects through the ring and into a peripheral groove 236 formed in the eccentric. Welded or otherwise secured to the ring 235 is a pull rod 237 which extends upwardly through an opening 238 in a foot 239 forming a part of a feeler bar 240 that is guided for up and down movement by suitably shaped yokes 241 and 242 secured to rails 207 and 208, respectively. A collar 243 adjustably secured to the rod 237 underlies a washer 244 which engages the lower surface of the foot 239 and thus effects upward movement of the rod 237 to the feeler bar 240. The upper end of the rod 237 carries an adjustable nut 245 which backs a washer that bears against the upper end of a coil spring 246 surrounding the rod, the lower end of the spring bearing against a flat face on the upper side of a slideable washer 247 with a convex lower surface that engages the foot 239 around the periphery of the hole 238. Downward movement of the pull rod 237 therefore transmits force to the foot 239 through the spring 246 and if the foot is not free to move the pull is absorbed by the spring and no damage can occur.

Each block 228 carries a stub shaft 247 upon which the hub 248 of an arm 249 is journaled and this arm projects over the eccentric 233. On this arm, there is a projecting lug 250 which is disposed beneath the head on the lower extremity of a screw 251 which is adjustably threaded into a threaded hole in the foot 239 and held in an adjusted position by means of a lock nut 252. The upper end of the feeler bar 240 has a horizontal extension 253 which overhangs the pile of sheets in the hopper and it is adapted to engage the top of the pile in the hopper when downward force is transmitted to the feeler bar 240 by the ring 235.

Each time a sheet is fed forward off the pile the feeler bar 240 swings downwardly and engages the pile. As the operation continues the height of the pile becomes lower due to the removal of sheets therefrom. When the lowered height of the pile allows the feeler bar to descend

low enough the screw 251 acts through the lug 250 and swings the arm 249 downward about its pivot 247, the high point of the eccentric being then below the shaft 186. If the downward swing of the arm 249 is sufficient, a pawl 254 pivotally mounted on the free end of the arm travels downwardly far enough to engage the next lower tooth on the rack bar 224. As soon as the high point of the eccentric again comes uppermost a follower wheel 255 carried by the arm 249 is raised by the eccentric and thereby acts through the pawl 254 to raise the rack a distance equal to the distance between consecutive teeth on the rack. When this happens the upward movement of the rack causes a second pawl 256 which is pivoted to the block 228 to snap under the next tooth of the rack and support the latter. The upper ends of the pawls 254 and 256 are pivotally connected with plungers 257 and 258 which extend through slots in the plate 57 and which are biased outwardly by springs 259 bearing against the heads of the plungers. The pawls are thus resiliently held in engagement with the toothed side of the rack.

In order to assist in the separation of the uppermost sheet of the pile when it is taken by the sucker heads, resilient wire fingers 261 may be mounted at the two front corners of the hopper. When the sucker heads pull the top sheet out from under these fingers and the carbon sheet from above these fingers, said fingers tend to retain the succeeding sheet on the pile and prevent it from adhering to and attempting to follow the top sheet. Removable screws 262 projecting through loops on the fingers serve to mount the fingers and permit them to be changed for other fingers having different characteristics to improve the sheet separating action and to compensate for differences in paper stock.

When it becomes necessary to replenish the sheets in a given hopper the operator may push in the plungers 257 and 258 and permit the plate 222 to descend until a stop pin 263 on the rack engages the uppermost guide 225. The plungers 257 and 258 are then released and the pile is built up to the desired height. Following this with the eccentric 233 turned to a position diametrically opposite to that shown in the drawing the rack 224 may be pushed up by hand to cause the top of the pile to engage the feeler rod extension 253. The wall of the hoppers thus filled, the suction may be turned on in the hollow shaft 170 and with compressed air imposed upon the tubular member 185, the motor may be started and the operation of all feeders may be begun. Directly after the rear edge of the sheet being fed passes beyond the extension 253 of the feeler bar, that bar is pulled down by the eccentric ring 235. If the stock being fed is light, a considerable number of reciprocations of the pull rod 237 may result merely in the compression of the spring 246 and the depression of the pawl 254 a distance insufficient to enable it to snap under the next lower tooth of the rack. In each cycle the eccentric raises the follower 255 slightly however and causes the pawl 254 to push the rack upward a distance less than the spacing of the teeth after which it descends until caught by the pawl 256. A constant slight jogging of the rack therefore takes place which has a beneficial result in jarring the sheets forward against the corner members 211 of the hopper to maintain an accurate pile.

As soon as the level of the pile descends sufficiently the screw 251, acting through the lug 250 on the swinging arm 249, depresses the pawl 254 into engagement with the next lower tooth, and the next upper movement of the eccentric functions through the follower 255 to raise the pawl 254 and push the rails upwardly, the pawl 256 then snaps into position beneath a lower tooth of the rack and supports it. The operation continues until the plate 222 has risen nearly to the upper limit of its movement when the machine should be stopped and the pile of sheets replenished. With the roll of carbon paper 9 positioned in the device at the top and rotatable on the shaft 19 the web 125 of this paper is carried downwardly, beneath the roller 33 and thence over the roller 35 and it is then

passed downwardly between the feed rollers 58 and 60 and the end of the strip extends between the blades 88 and 89 following which the solenoid 108 may be given one impulse to cause the knife 88 to advance toward its mate 89 and thereby the carbon paper is cut off even with the lower surface of the blade 89. Now with the indexing arm 53, a setting is made according to the length to which the carbon paper is to be cut. Such a setting is made by loosening the nut 55 and moving the indexing arm 53 to a desired position along the sector 50, the surface of the sector 50 being calibrated to facilitate such settings. As the sheet stacking mechanism, with which my device cooperates, moves to transfer a sheet of paper from a stack to an adjacent station (an operation which will more fully be understood when the description of both mechanisms has been completed), the carbon web 125 passes between the knives and down into the arcuate guide or chute 134. The portion of the web within the guide or chute 134 remains integral with the web until its leading edge reaches a point between the suckers or suction cups 199, 202. At that instant the suction cup 199 is swinging down on the carbon paper, the solenoid 95 is energized to cut the sheet of carbon paper from the web. From this, it is quite evident that the desired sheet of carbon paper is at all times positively controlled—first it is mechanically controlled as the web is pulled off the roll and as the leading edge of the web traverses the chute and up to the point where said leading edge reaches a point beneath the then descending suction cup 199. Then as the suction cup is taking over the control, the carbon sheet is cut off from the web, and the carbon sheet is reinforced by the heavier paper sheet at the top of the pile and is prevented from being ruptured by the suction.

Since the Macey patent referred to above does not show mechanism for oscillating the shaft 187 and the arm 198 carried thereby and for other movements and functions described in said patent, I have provided diagrammatic Figures 13, 14 and 15 and have incorporated in the circuit diagram Figure 12 a means on the cam for oscillating the suction cups, a pin 270 carried by a cam 271 which is keyed to and movable with the shaft 192. A bell crank 272 pivoted at 273 has an arm 274 the extremity 275 of which is curved upwardly to be engaged by the pin 270. The bell crank 272 also has an arm 276 which carries a button 277 formed of insulation. A spring 278 urges the bell crank 272 in a clockwise direction, and spaced apart therefrom is a stop 279. A contact arm 280 which may be formed of spring bronze for example carries a contact point 281. Mating with the contact point 281 is a contact point 282 carried by a contact arm 283. When the bell crank 272 is not actuated by the pin 270 the contacts 281 and 282 are open. On the other hand when the bell crank 272 is engaged by the pin 270 the contacts are closed. The contact arm 280 is connected via a fuse 284 to one side of a source of power 285. While the other side of said source is connected via a fuse 286 to a bus line 287 which has several parallel connections one of which is a connection 288 to one terminal of the winding of a relay 289, and the other terminal of the winding is connected via a wire 290 to the contact arm 283 and thus when the contact points 281 and 282 are closed the relay is energized. However, when the machine comes to rest with the contacts closed, the winding on the relay together with a retarding copper slug 291 on the armature end of the winding cuts the circuit to the solenoid, which circuit is as follows:

The solenoid 108 which actuates the knife 88, 89 for cutting off a sheet of carbon paper from the carbon paper web has one terminal connected to the bus line 287 via a branch wire 292 and the other terminal is connected via a branch wire 293 to a bus connection 294. This bus connection carries a contact 295 which is contacted by the relay arm 296 and the relay arm in turn is connected to the wire 290 and consequently in com-

mon with the second mentioned terminal of the relay winding and the contact arm 283. Connected in parallel with the wires 290 and 294 are a high resistance 297 and a capacitor 298. The winding of the relay 289 has a high resistance and will not heat up even though it may be energized continuously for a long period of time. Also the solenoid must cause the blades 88 and 89 to chop the carbon paper sheet off the web of carbon paper and immediately restore the blade 88 to its normal position and thereby keep the passage 134 of the upper end of the chute open so that the carbon paper web may enter and follow said passage 134. The circuit diagram in Figure 12 shows several other solenoid connections which are identical with the ones just described and it is believed unnecessary to repeat the description of the several identical solenoids the number of which will be in accordance with the number of stations on the collating machine.

Now in order to oscillate the arm 198 of the Macey mechanism, which is carried on a shaft 187, reference is made to Figure 13 wherein a lever 299 has a hub 300 which is keyed on the shaft 187, which is the main shaft carrying the oscillating arms 198, by means of a key 301.

Keyed on the shaft 193 is a crank 302, by means of a key 303. The crank arm has a hole therethrough to accommodate a clevis pin 304 which also extends through a corresponding hole in a connecting rod 305, and a clevis pin 306 extends through said hole and a second hole in alignment therewith formed in the extreme end of the lever 299. It will be understood that the crank arm 302 and the lever 299 are just beyond or they at least clear the end of the shaft 193, as the shaft is rotated. This arrangement may be more clearly seen in the diagrammatic representation, Figure 15. As the shaft 193 is rotated, for example by means of a motor 307 (Figure 15) it rotates a shaft 308 with a worm 309 keyed thereto. Meshing with the worm 309 is a worm gear 310 which is keyed on a shaft 311. The shaft 311 carries in driving relation a star wheel 312 which forms a part of a clutch 313. The clutch 313 also includes a disk 314 which is keyed to a shaft 315. The disk 314 carries a stud 316 upon which a lever 317 is pivotally carried. The lever 317 has a hook-like portion 318 on one end thereof and connected to the portion 318 is one end of a spring 319. The other end of the spring is connected to a spring post 320 carried on the disk 314. The disk 314 also carries a post 321 which constitutes a stop for limiting the movement of the lever 317 about its pivot 316 in a clockwise direction. The hook portion 318 of the lever engages one of the teeth of the star wheel in the manner shown in dotted lines at 318a. Normally the hook portion 318 remains in engagement with one of the teeth of the star wheel 312 and a lever 322. Fixed on a shaft 323 in the dotted position 322a and the motor through the medium of the worm 309, the worm gear 310 and the shaft 311 drives the shaft 315 due to the engagement of the lever 317 with the star wheel 312 and while the clutch 313 is rotating the portion 324 projects beyond the periphery of the disk 314 due to the fact that the lever 322 is normally swung out of the path of the portion 324 and as this occurs a spur gear 325 which is keyed on the shaft 315 drives a second spur gear 326 with which it is meshed and this gear which is keyed on the shaft 193 positively drives said shaft and in so doing it oscillates the arm 198 which carries the shaft 170. This shaft supports a series of pairs of suction cup supports 201, said suction cups being shown at 199 and 202 in Figures 1 or 4, for example. Now as the shaft 193 rotates the swinging arm 198 traverses a path which extends from the solid position shown in Figure 4 to the position shown in dotted lines.

Now in order to cause the suction cups 199 and 202 to pick up the paper sheets from the stack or pile and at the same time pick up the end of the carbon sheet being severed from the web a rocking motion of the suc-

tion cups at each extreme position of the suction cups is necessary and such an arrangement is shown in Figure 14.

Referring now to Figure 14, the suction cups 199 and 202 are carried in the holder 201 which is in turn secured on the shaft 170 independently of the swinging movements of the lever 193. As a matter of fact the machine may have two such arms 198 moving in unison and commonly supporting the shaft 170 and with the shaft 170 journaled in the extremities of the elements 193, suction cup holders 201 may be fixed on the shaft 170 and at the same time a lever 327 may also have a split boss clamped onto the shaft 170 so that when this lever is moved upwardly or downwardly the holder 201 and the suction cups carried by the latter are moved in unison. Connected to the lever 327 by means of a clevis pin 328 extending through aligned holes is a connecting rod 329, and the other end of the connecting rod is connected to a lever 330 by means of a clevis pin 331 passing through aligned holes in the lower end of the connecting rod 329 and the upper right hand corner of the element 330. The shaft 193 also carries a cam 340 and this cam is keyed on the shaft 193 and carries opposed lobes 341 and 342. As the shaft 193 rotates the lobes 341 and 342 successively engage the roller 339 and cause the lever 330 to rock about its axis 332 and this movement, through the medium of the connecting rod 329, is imparted to the lever 327, the shaft 170 and the suction cup holders carried thereby. Now when one of the lobes (the lobe 341 for example) is in engagement with the roller 339 the suction cups 199 and 202 are in the position shown in Figure 1, just picking up the sheet of paper and the sheet of carbon the latter which has just been severed from the carbon paper web 125. Now when the cam lobe 342 is in engagement with the roller 339 the connecting rod 329 has moved to the position 329a shown in dotted lines and at the same time the arm 198 has moved over to the position shown in dotted lines in Figure 4. Now in the first position, as will hereafter be explained, the suction is supplied to the suction cups 199 and 202 while in the position shown in dotted lines in Figure 4, the suction has ceased and in its place has been substituted pressure to rapidly disengage the paper and the carbon paper from the respective suction cups.

As the stations (between the arms 190 on the chain 191) along the surface 188 must be moved in definite time relation with the other elements, I provide a miter gear 343, and meshing with the miter gear 343 is a second miter gear 344 which is carried on a shaft 345 and this shaft carries on its extremity a sprocket 346 with which the chain 195 is engaged, so that by this arrangement the stations are advanced along the surface in time with the other movements. The lever 322 on the shaft 323 which has been described above as normally out of the path of the extremity 324 of the lever 317. Now a handle 347 is fixed on the shaft 323 and it has a toggle arrangement 348 which functions to lock the lever 322 out or in. For example the solenoid 95 may throw the lever 317 in to stop the machine whenever an automatic control thereon signaled the absence of one sheet or the presence of two sheets. As pointed out above, when said lever 322 is out, it keeps the machine running, and when permitted to go in it stops the machine on index at zero.

Carried on the shaft 308 is a pulley 349, and a belt 350 embraces and spans the pulley 349 and also a pulley 351 carried on the shaft 352 of a blower 353. A manifold 354 forms the inlet of the blower and is in turn connected to a conduit 355 and this conduit has a branch 356, which communicates with the atmosphere, while the valve 357 is in the position 357a, and when the valve is in the other position indicated by the numeral 357, communication with the atmosphere is nullified. When the valve 357 pivoted at 358, for example, is in its normal position indicated by the dotted line 357, the branch 356 is not under the influence of the partial vacuum or negative

pressure. When in the dotted position shown at 357a the branch 356 is under the influence of the negative pressure. Other branches may communicate with the conduit 355, for example a branch 359 may be connected to the conduit 355 and the connection may include a valve 360, which, when in the position shown at 360 excludes the suction or negative pressure from the branch 359. This valve when in the position 360a subjects the branch 359 to the influence of the partial vacuum and this branch 359 is connected to the conduit 200 which communicates with the interior of the hollow shaft.

The blower has an output conduit 361 to which a distributing conduit 362 is connected. The conduit 362 has a branch 363, and spaced apart therefrom is a second branch 364, both of these branches are open to the atmosphere, and connecting the conduit 362 to the conduit 355 is a branch conduit 365 which extends from the conduit 362 to the conduit 355 in a manner to be controlled by the valve 360. This means that when the valve 360 is in the position indicated at 360 by a solid line, positive pressure is delivered via the branch 359 and into the conduit 200. On the other hand when the valve is in the dotted position 360a, the branch 359 and the conduit 200 connected thereto is removed from the influence of the pressure and is subjected to the partial vacuum, and also to the conduit 355. When the valve 366 by a solid line is in the position indicated at 366, pressure from the conduit 362 discharges into the atmosphere via the branch 363. When the valve is in the position indicated by a dotted line at 366a, the pressure is prevented from passing to the atmosphere via the branch 363. The valve when in the position shown by a solid line at 367 prevents air in the conduit 362 from passing into the conduit 365 and instead is delivered via the branch 364 and a connection to the conduit 362. On the other hand when the valve is in the position shown by a dotted line at 367a, air is prevented from entering the branch 364 and is delivered via the conduit 365 to the conduit 200 when the valve 360 is in a position from shutting off communication with the conduit 355 and thus air under pressure from the conduit 362 is delivered to the suction cups 199 and 202 and thereby the sheets which were picked up by the suction cups and moved over to a position above the tray 188 and thus the suction which was holding the sheets to the cups is suddenly nullified and replaced by pressure and thereby the sheets are quickly released from the suction cups.

The timing of the air system

The valves 357, 366, and 367 may be butterfly vane valves and they are timed for example as follows. At zero degrees of any operating cycle in which case the machine is at rest, the valves 357 and 366 are open to the atmosphere. Now at approximately ten degrees after the next machine cycle starts, the valves 357 and 369 connect the suction to the conduit 200 and at substantially the same time, the valves 366 and 367 connect the pressure or exhaust from the blower 353 to the conduit 262. Now at approximately one hundred eighty degrees after the start of said cycle, the valve 357 connects the suction conduit to the atmosphere while the valves 360, 367, and 366 connect the pressure or blower to the conduit 262. The cycle continues and at approximately two hundred ten degrees of the cycle the valves 357 and 366 open so as to subject the interiors of the conduits 355 and 362 to the atmosphere. Each successive cycle will operate satisfactorily if they are duplicates of the cycle just described.

Although I have not shown any means for operating these valves (the arrangement being schematic in Figure 15), cams to operate these valves may be positioned on either the shaft 193 or the shaft 315 and such cams would have lobes thereon which would actuate the valves specified above at the degrees specified of the operating cycle of the machine.

Setting up for a specific size of carbon sheet

The first step in making such a set up is to loosen the screws 39 (Figure 1) thereby unclamping the plate 36 from the plate 10, and loosening the clamping screws 39 (Figure 4) thereby unclamping the plate 38 from the plate 11, and leaving the sub-assembly 36, 38 free to be rotated about the shaft 37 as an axis.

If the sub-assembly is rotated in a clockwise direction, as viewed in Figure 1, the guide 135 telescopes into the guide 133 for example, and the sub-assembly is rotated in the proper direction (according to the length of the carbon paper to be severed from the web of carbon paper 125) and when a point is reached where the curved length within the guides 133, 135 from the knife 88, 89 to a point between the suction cups 199, 202 is the required length. The screws 39 are again tightened to retain that setting.

For lengths shorter than the telescoped length of the guides 133, 135, remove these guides and set the assembly so that the distance between the knife 88, 89 to the point between the suction cups is the required length, thus the device may be set up for a wide range of lengths. Incidentally the lengths referred to are actually the widths of the carbon sheets, while the length is actually the width of the roll 9.

The next step in the set up is to loosen the locking nut 55 and swing the arm 53, Figure 1, over the scale 50 to a position where the pointer 54 is in line with (or over) an indication of the exact length desired, which also corresponds to the setting described in the first step, and this setting is retained by tightening the locking nut 55, and it controls the amount of rotation of the feed rolls 58 and 60 (Figures 1, 4 and 8).

When the pulling web 168 is pulled by the movement of the swinging arm it rotates the element 164 which is free on the shaft and carries a pin 171. This pin cooperates with the squared end 176 of the pawl 174, which is pivoted on stud 175 carried by the member 173 (the latter being keyed on the shaft 37). Now as the element 164 is rotated by the pull of the web 168 it is moved in a counterclockwise direction (as viewed in Figure 4) exactly one revolution, or 360°. On the reset half of the cycle, the pin 171 is rotating in an opposite or clockwise direction for 360° plus a slight additional clearance, so that when it comes to rest it is a fraction of an inch in front of the pawl 174. For an understanding of how the member 164 is rotated in a clockwise direction, reference is made to Figure 4 and as the reset half of the cycle starts, the member 20 with the suction cups is in the position shown in dotted lines and during said reset cycle it moves to the position shown in solid lines above the pile of papers, so that the pulling web 168 is moved to the left, as seen in Figure 4, thence around the pulley 171 and up to and around the pulley portion of the element 164, thereby allowing the latter to rotate in a clockwise direction under the urge of the belt member 163 which is powered by a spiral spring within the drum portion 161.

Referring now to Figure 1, the arm 52 is keyed on the shaft 37 by means of the cap screw 51. The arm 52 carries a lug 141 and this lug engages a lug 144 on the bell crank 140 which is pivotally mounted on a stud 142 carried on the disk 48. As the shaft 37 rotates, the arm 52 picks up the pawl 143 thereby rotating the disk 48 in a clockwise direction, as seen in Figure 1, until the end of the pawl 143 contacts the projection 57 of the set arm 53. This arm as will be remembered, is locked and fixed due to the clamping action of the thumb screw 55 and therefore a slight rotation in a clockwise direction is made by the bell crank pawl 143 and this causes the lug 140 to be moved out of the path of the lug 141 carried by the arm 52. As a result of this action, the disk 48 is disengaged or freed from the shaft 37. Now the angular movement traversed by the disk 48 under the pull of the belt 158 has caused the feed

rollers 58 and 60 to rotate such a distance that the surface travel of the rollers 58 and 60 has advanced the carbon web the exact distance for which the setting above described was made.

It must be borne in mind that the arm 53 is not keyed to or fixed on the shaft 37 and also that the disk 48 does not rotate instead it moves back and forth.

With the set-up as above described, the machine may be caused to operate as many cycles as necessary for the given size of carbon paper and when the device is to be set up for a different size, the same procedure as described above may be followed.

Although I have herein described, by way of example, one preferred embodiment of the invention it will be understood that I am not to be limited to the exact details disclosed, as many changes may be made in the arrangements shown and described, within the scope of the following claims.

I claim:

1. In combination with sheet handling apparatus wherein sheets of paper are carried in stacks, means to support a roll of carbon paper and means to unreel a web therefrom, means to guide a leading edge of said web to a position on one of said stacks, a device operating cyclicly and comprising a suction cup for each stack of said papers for engaging, lifting and moving both the top sheet of said stack and another sheet positioned thereon, with a thin carbon sheet being positioned on a relatively stiff lower sheet, to another location, a second suction cup adjacent to and movable with said first suction cup, means to sever a sheet of carbon paper of a pre-determined length from said web as said second suction cup engages it adjacent to the leading edge thereof, and means to conjointly raise and move said suction cups, said top sheet and said sheet of carbon paper to said other location, and means to release said sheets to said other location and to return said suction cups to their initial positions and means for controlling the motion of the second suction cup so that it is coordinated with the cutting of the carbon, said carbon paper and paper sheet being moved together by both said cups.

2. In combination with sheet handling apparatus wherein sheets of paper are carried in stacks, a device operating cyclicly and comprising a suction cup for each stack of said papers for engaging, lifting and moving both the top sheet of said stack and a fragile sheet that may be deposited thereon to another location, a second suction cup adjacent to and movable with said first suction cup, means to support a roll of carbon paper, means to unreel a web of said carbon paper from said roll, cutting means adjacent to said web, means to guide said web from the unreeling means to a point on said stack beneath one of said cups, means to actuate said cutting means and sever a sheet of carbon paper of a pre-determined length from said web immediately after a leading edge thereof has contacted said top sheet and immediately after it has been engaged by said suction cup adjacent to the leading edge of said carbon, and means to conjointly raise and move said suction cup, said top sheet and said sheet of carbon paper to said other location, and means to release said sheets and to return said suction cup to its initial position.

3. In combination with sheet handling apparatus wherein sheets of paper are carried in stacks, a device operating cyclicly and comprising a suction cup for each stack of said papers for engaging, lifting and moving the top sheet of said stack and a fragile sheet that may be deposited thereon to another location, a second suction cup adjacent to and movable with said first suction cup, both said cups being initially spaced apart from said sheet, means to support a roll of carbon paper thinner than said sheets, settable cutting means and controls therefor for controlling the length of a sheet of carbon paper to be cut from said web, means to guide said web to a point on said last stack beneath one of said cups, means under control of said settable means for severing a sheet of

carbon paper from said web at least as said suction cup is engaging said carbon sheet near its leading edge, means to conjointly raise and move said suction cups, said top sheet and said sheet of carbon paper to said other location, means to release said sheets at said other location, and means to return said suction cups to their initial positions.

4. In combination with sheet handling apparatus wherein sheets of paper are carried in stacks, a device operating cyclicly and comprising a suction cup for each stack of said papers for engaging, lifting and moving the top sheet of said stack and any other thinner sheet that may be deposited thereon to another location, a second suction cup adjacent to and movable with said first suction cup and both being normally positioned in spaced apart relation to said sheets, means to support a roll of carbon paper, means to unreel a web of carbon paper from said roll, means including cutting means adapted to be pre-set for controlling the length of a sheet of carbon paper to be cut from said web, transporting rollers and guide means adapted to guide said web and to bring its leading edge to a point on said stack beneath at least one of said cups, means under control of said settable means for severing a sheet of carbon paper having a length substantially equal to said pre-set length as said second suction cup is in the act of engaging said carbon sheet adjacent to its leading edge, thereby insuring continuous control of said carbon until said cups engage the same; means to conjointly raise and move the suction cups, said top sheet and the sheet of carbon paper to said other location, means to release said sheets at said other location by cutting off the suction from said cups and delivering thereto a light pneumatic pressure, and means to return the suction cups to their initial positions.

5. In combination with sheet handling apparatus wherein sheets of paper are carried in stacks, a device operating cyclicly and comprising a suction cup for each stack of said papers for engaging, lifting and moving the top sheet of said stack to another location, a second suction cup adjacent to and movable with said first suction cup, means to support a roll of carbon paper, means to unreel a web of carbon paper from said roll, means adapted to be pre-set for controlling the length of a sheet of carbon paper to be cut from said web, an electrically actuated knife comprised of a pair of cooperative blades which are normally separated, guide means between said knife and said stack, transporting rollers engaging said web and adapted to guide it between said blades and through said guide means, control means for said electrical means made effective in time with the arrival of the leading edge of said web to a point on said stack beneath said second mentioned suction cup; means to conjointly raise and move said suction cups, the top sheet of said stack, and the severed sheet of carbon paper to another location; means to supply negative pressure to both said suction cups, means to conjointly raise and move the suction cups and the sheets engaged thereby; said top sheet being engaged by said first suction cup, and the sheet of carbon paper, reinforced by said first sheet, being engaged by said second cup; means to disconnect said negative pressure from said cups and to momentarily supply positive pressure thereto, thereby rapidly releasing said sheets and allowing them to fall in said other location, and means to return the suction cups to their initial positions.

6. In combination with a collating machine wherein sheets of paper to be collated are arranged in piles said machine having a swinging arm operating cyclicly and carrying pairs of suction cups, means to supply a partial vacuum to said cups during a pre-determined portion of the cycle and means to momentarily supply air under pressure to said suction cups, a frame, means to support a roll of carbon paper for rotation on said frame, rotary dial means adapted to be set for controlling the length of a sheet of carbon paper to be cut from said web, an electrically actuated knife comprised of a pair of co-

operative shearing blades which are normally separated, guide means between said knife and said stack having its entrance aperture substantially in alignment with the space between said blades, transporting roller means engaging said web and adapted to propel it between said blades and through said guide means to a point adjacent to one of said suction cups, control means for said electrical means made effective in time with the arrival of the leading edge of said web to a point on said stack beneath said last mentioned cup, means to supply negative pressure to both said suction cups, means to conjointly raise and move the suction cups and the sheets engaged thereby; said top sheet being engaged by said first suction cup, and the sheet of carbon paper, reinforced by said first sheet, being engaged by said second cup; means to disconnect said negative pressure from said cups and to momentarily supply positive pressure thereto, thereby rapidly releasing said sheets and allowing them to fall in said other location, and means to return the suction cups to their initial positions.

7. In combination with a collating machine wherein sheets of paper to be collated are arranged in piles said machine having a swinging arm operating cyclicly and carrying pairs of suction cups, means to supply a partial vacuum to said cups during a pre-determined portion of the cycle and means to momentarily supply air under pressure to said suction cups, a frame, means to support a roll of carbon paper for rotation on said frame, rotary dial means adapted to be set for controlling the length of a sheet of carbon paper to be cut from said web, a knife comprised of a pair of cooperative shearing blades which are normally separated, a solenoid having a movable member operatively connected to one of said blades for actuating the same, guide means between said knife and said stack having its entrance aperture substantially in alignment with the space between said blades, transporting roller means engaging said web and adapted to propel it between said blades and through said guide means to a point adjacent to one of said suction cups, control means for said solenoid made effective in time with the arrival of the leading edge of said web to a point on said stack beneath said last mentioned cup, means to supply negative pressure to both said suction cups, means to conjointly raise and move the suction cups and the sheets engaged thereby, said top sheet being engaged by said first suction cup, and the sheet of carbon paper, reinforced by said first sheet, being engaged by said second cup; means to disconnect said negative pressure from said cups and to momentarily supply positive pressure thereto, thereby rapidly releasing said sheets and allowing them to fall in said other location, and means to return the suction cups to their initial positions.

8. The invention according to claim 6 in which said frame is comprised of two parts, one of which is fixed and the other of which is movable for setting the device for handling longer or shorter carbon sheets.

9. The invention according to claim 8 wherein said frame is comprised of a main frame and sub-frame adjustably carried on said main frame and movable on an axis substantially coinciding with the axis of said rotary dial means.

10. The invention according to claim 7 in which feed means for said rotary dial means is driven by flexible pulling means powered by said swinging arm.

11. The invention according to claim 10 in which spring drum means operatively connected to said flexible pulling means functions to urge elements moved by said pulling means to their normal or reset positions during each operating cycle of the machine.

12. The herein described method of handling thin carbon paper which comprises; the step of positioning a portion of a continuous web of said carbon; adjacent a paper web which is thicker than said carbon, whereby said carbon may be superimposed on said paper web; the step of subjecting a zone adjacent to the leading edge

of said portion and a corresponding edge of said paper web to the influence of a negative pressure; the step of severing said portion from said web at the moment of application of said negative pressure, so that said portion is under positive control all the time; and the final step of simultaneously moving both said portion and said web from the position where said web was located to a wanted new position, said paper web being the thicker sheet and serving to carry the severed sheet from the carbon web and protecting the severed carbon web from damage and curling during handling by the application of said negative pressure when being transported by the application of said negative pressure.

13. In a device of the character described, means to hold and support a stack of cut sheets, one edge of the uppermost sheet in said stack being termed an index line, means to support a roll of carbon paper, means to withdraw a carbon web from said roll and advance the leading edge of said web over the surface of said stack substantially to said index line, cutting means to sever said web from said roll, whereby said web will have a pre-determined length, a unitary structure supporting said advancing means and said cutting means, said structure being pivotally carried on said device, means to set said cutting means with respect to said index line in accordance with the length of carbon web desired, and means to move said carbon web and said uppermost sheet from said stack to a position adjacent thereto, and the pivot connection between said unitary structure and said device controlling the length of the sheet cut.

14. The invention according to claim 13, in which said means to move said carbon and said sheet are comprised of a moving arm carrying suction cups that are supplied with negative pressure, and means to remove said negative pressure from said cups and to deliver thereto a light pneumatic positive pressure for overcoming said suction and quickly releasing said sheets to said position.

15. A device according to claim 13, in which a telescoped arcuate guide for said carbon web includes one element which is secured to said unitary structure and a cooperative element which is fixedly connected to the support for said cut sheets.

45

16. A machine for assembling carbon paper sheets with relatively stiff paper sheets, comprising a support for a pile of stiff paper sheets, means for supporting a web of carbon paper, a feed chute through which said web of carbon paper is fed to said stiff paper sheets, means to cut a sheet of carbon paper from said web whereby the carbon paper sheet is superposed on the stiff paper sheet, a tray, having a longitudinal slot, in juxtaposition to said support, a plurality of spaced pins extending through said slot, a rotatably endless chain on which said pins are mounted, a plurality of spaced hoppers on said endless chain spaced apart the same distance as said pins, means for intermittently advancing said endless chain a distance equal to the spacing between said pins, suction means comprising two suction cups to remove sheets from said hoppers, one suction cup engaging a stiff paper sheet and the other suction cup engaging a carbon paper sheet, and means for moving the suction cup means whereby an assembly of a stiff paper sheet and a carbon sheet is moved as a unit, the carbon sheet being backed up by the stiff paper sheet to prevent curling and damage to the carbon sheet.

17. A method of handling carbon sheets to prevent curling and damage thereof, which comprises feeding a web of carbon paper to a supply of stiff paper sheets, cutting said web of carbon paper into sheets and assembling said carbon paper sheets with said stiff paper sheets so that the stiff paper sheets reinforce the carbon paper sheets, applying negative pressure to the assembly of stiff paper and carbon paper sheets with the stiff paper sheets preventing the rupture of the carbon paper sheet and transporting the assembly while the same is held by said negative pressure to a predetermined position.
